UNITED STATES PATENT OFFICE.

VICTOR BURSCHEL, OF SCRANTON, PENNSYLVANIA.

DESIGN FOR A PRINTED FABRIC.

No. 38,589.

Specification for Design.

Patented May 28, 1907.

Application filed May 2, 1907. Serial No. 371,551. Term of patent 7 years.

To all whom it may concern:

Be it known that I, VICTOR BURSCHEL, a citizen of the United States, residing at Scranton, in the county of Lackawanna and State of Pennsylvania, have invented a new, original, and ornamental Design for Printed Fabric.

The figure is a plan view of the printed fabric, showing my new design.

I claim:
The ornamental design for printed fabric,
as shown.

VICTOR BURSCHEL.

Witnesses:

JOHN J. DURKIN,
JOHN J. TOOHEY.
